CLAMP ON PAPER CUTTING MACHINE

Fritz Laessker, Chemnitz, Germany

Application May 22, 1935, Serial No. 22,874

10 Claims. (Cl. 164—51)

The invention relates to improvements on paper cutting machines, by which springs or other elastic means, operated by the driving mechanism, produce the pressure in the clamp to hold the stock during the cut.

Among the objects of the invention are:

First.—Simple means, which produce a pressure in the clamp during the whole cut, nearly independent of the increasing or decreasing tension of the elastic member, and hold the stock during the cut in the most favorable manner, consisting in: highest pressure at the moment the knife cuts into the stock and decreasing pressure in expiration of the cut.

Second.—Further arrangements of the means which allow a high increase of the pressure up to the moment the knife starts the cut for the purpose to have a smooth, quiet and shakeless working clamp.

Third.—Means for an improved adjustment of the pressure amount, to meet proper clamping of soft and hard stock.

Further objects of the invention and details of mechanism shall appear from the description and the claims which follow.

I attain these objects by mechanism illustrated in the accompanying drawings, in which

Fig. 1 is a front view of the machine, showing the clamp, knife and driving mechanism in resting position, wherein the highest paper pile is seen in the machine.

Fig. 2 shows main part of the transforming mechanism in right angle cross section on line 1—1 Fig. 1 of the front view.

Fig. 3 is a view of the driving mechanism looking in the direction of arrow 2 in Fig. 1.

Fig. 4 shows the balance mechanism of the clamp in position at the end of the cut, clamping the highest paper pile.

Fig. 5 shows the same position of the driving mechanism as in Fig. 4, clamping no stock.

Figs. 6 to 11 inclusive show certain arrangements of the balance mechanism which obtain a pressure variation during the cut.

Figs. 6a—11a illustrate the variation diagrammatically.

In the paper cutting machine, shown in Fig. 1, the gear 1 has its bearing on the machine body 2 and is driven over a clutch by an electric motor neither the clutch nor the motor being shown. On a shaft 4 mounted in the frame of the machine is a gear 3 having an eccentric 5 integral therewith.

A connecting rod 6 is secured to the eccentric 5 and by pin 7 to a two-arm lever 8. The latter

is turnably mounted on pin 9 which is fixed on the machine body 2 (see also Fig. 3). Lever 8 carries pins 10 and 12 respectively at the free ends of its arms 8' and 8''. Rotation of the eccentric 5 produces a swing motion of lever 8 which drives with the pin 10 the knife 11 and with the pin 12 the clamp.

The knife 11 is slidably mounted in the machine body 2 above the table 13 which is part of the machine body and carries the paper pile 14. 10 Usually the movement of the knife takes place in an angle of about 45 degrees to the table. Therefore, the knife 11 has slots 15, arranged in this angle, and sliding blocks 16, mounted on pins 17 which are fixed to the machine body 2, fitting 15 in these slots 15 and guiding the knife.

The connecting rod 18 is pivoted by 10 to the lever 8, by 19 to the knife 11. One revolution of the eccentric 5 causes a complete downward cutting and upward return motion. The press beam 20

20 is movable in a right angle direction to the table surface and mounted (see Fig. 1) behind the knife 11. Connected by pins 25, the press beam is carried by connecting-rods 26, which are pivoted by pins 27 to transmitting-levers 28 and 29. 25

These levers are turnably mounted on pins 30 and 31 which are fixed to the machine body 2. The connecting rod 32, pivoted to the levers 28 and 29, takes care of a parallel motion of the press beam to the table surface and transmits the power from lever 28 to lever 29. Spring 33, arranged 30

between lever 28 and pin 34 which is fixed to the machine body 2, carries the weight of the press beam and gives it a soft upward motion, so that the slot 35 of lever 28 and the pin 36 of the transforming lever 37 fix the limit of this upward motion.

I now describe the most important part of the invention, the balance mechanism. It consists 40

(see Fig. 1) of the power-transforming lever 37, the connecting-rods 38, 38', of a hollow shaft 39 with the extension 40 and the compression spring 41. With pin 36 the transforming lever 37 is secured to the transmitting lever 28. The trans-

mitting lever 37 is also pivotally connected to the connecting rods 38, 38', which in turn are pivoted on pin 12 on which pin are pivoted the two- 45

armed lever 8 and the shaft 39. Shaft 39 carries nuts 43 which are provided for tension adjustment of the spring 41. The shaft 40 is slidably 50

mounted inside of the pipe shaped shaft 39. In the slot 44 of shaft 39 moves a pin 45, secured to the shaft 40. Between the nuts 43 and the head 46 of shaft 40 is mounted the spring 41. The head 46 is turnably secured to the transforming 55

lever 37, and its distance to the pin 42 is also adjustable by hand (see Fig. 2). For this purpose the arms 37" of the transforming lever have slots 48 and a bushing 49 as bearing for head 46 is slidably mounted in the slots 48. A head-screw 50 going through the bushing 49 and the slots 48 can be tightened by a nut 51, so, that the bushing 49 is fixed at the desired distance from the pin 42. Head 46 is always turnable on the bushing 49. The operation of the clamp of the above described paper cutting machine may be explained as follows: Pin 12 of the two-arm lever 8 receives by turn of 180 degrees of the excentric 5 a motion, giving it the position as shown in Figs. 4 and 5. The tension of the elastic member during this motion depends on the height of the paper pile. Fig. 4 gives the position of the single parts of the balance mechanism, clamping the highest pile of stock, which is designated by reference character 14 in Fig. 1. Then the press-beam 20, the connecting rods 26 and the transmitting lever 28, 29 cannot take part in the motion of the lever 8. Hence spring 41 is pressed together by turn of the transformer lever 37 around the pin 36, and around pin 42. This turn is obtained by motion of the connection rods 38, respectively by excentric 5. Without any pile on the table 13, Fig. 5 shows this position of parts of the balance mechanism. There is the same, not increased tension of the spring 41 as in Fig. 1. In this case of Fig. 5 the press beam 20, the transmitting lever, connecting-rods and elastic member share in the motion of the driving excentric 5. It is to be understood, that the press-beam 20 starts its down-motion with the turn of the driving-excentric 5, and all parts of the balance mechanism take part in this motion until the press-beam 20 reaches the pile. Then the balance mechanism starts its action. The spring is pressed more together and the pile under pressure, no matter what the height of the pile between zero and the maximum. The spring tension increases after this meeting, until a turn of 180 degrees of the excentric 5 is obtained.

45 The down motion of the knife will start also with the turn of the driving-excentric and be finished with 180 degrees of its turn. It follows: the knife and the clamp are working in the same phase. It is necessary that the cut starts not before the stock is pressed hard enough by the clamp, as to be unmovable. To obtain this certain time difference between the beginning of pressure on the pile and the starting of the cut, arrangements in the driving mechanism of the knife are provided. The arm 8" of the two-arm lever 8 and the connecting rod 18 therefore include, at their rest position (see Fig. 1) an angle of about 180 degrees, which decreases with the turn of the excentric 5 to about 90 degrees. With 50 the start of the turn of excentric 5, the lever 8 receives a motion whose speed is transmitted directly to the clamp by the fact of the direct driving positions of the levers 8', 28 and 29. But the speed of lever 8" is transmitted to the knife 55 by connecting-rod 18 in an increasing ratio, until lever 8 has its about right-angle position to connecting rod 18 at 180 degrees turn of the driving excentric, that is to say, during the beginning of the down-motion of the clamp the knife goes 60 down with a lower speed and stands back to the motion of the clamp. Because the speed of the knife increases, clamp and knife reach their lowest position (the table) about the same moment. It is very advantageous, that the knife starts the 65 cut at the moment of the highest pressure in the

clamp, which is obtained by this described driving mechanism of the knife and the clamp.

Both, the knife and clamp, are moved back to its rest position by turn of the excentric 5 from 180 to 360 degrees. The rest-position is shown in Fig. 1.

The transmitting-lever 28 is provided with a slot 35 which is a section of a circle. The slot allows a down movement against the tension of spring 33. This movement is wanted to control 10 the distribution of the lines with one side of the press beam.

As to show clearly the single advantages and possibilities of the invention and how the transformed pressure is obtained, the further description shall be made on the diagrammatical views of Fig. 6 to 11, where all unnecessary parts of the cutting machine are omitted.

In Fig. 6 the transmitting lever 128 replaces lever 28 of Fig. 1; transforming-lever 137, connecting-rod 138, shaft 139 and spring 141 are in the place of parts 37, 38, 39 and 41 of Fig. 1. In Fig. 6 is the driving excentric 105 directly connected to shaft 139 and connecting-rod 138, and has its bearing on the machine body 102. Diagram Fig. 6a shows in direction of arrow P the pressure amount appearing in the press beam, and in direction T the turning degree of driving excentric 105. During the cut of the highest pile the spring tension increases from the amount 30 f to f' , see line 160, the arm 137" of the transforming lever decreases its effective arm length from g to g' , and the arm 137' keeps about its effective length h . The torque, produced by the spring tension and the arm of spring attack is 35 alike the torque obtained by the arm of pressure transmission and the pressure in the clamp.

$f.g = h.P$ at zero position of excentric 105

$f'.g' = h.p$ at 180 degrees position of excentric 105 40

In the sample of Fig. 6 the spring tension increases from $f=100\%$ to $f'=200\%$, and the effective length of arm $g=100\%$ decreases to $g'=50\%$. That means, at the zero and 180 degrees positions of the excentric 105 the pressure in the transmitting lever 128 is equal, as indicated by line 161 45 Fig. 6a. The measurement of spring tension f and length of the arms g and h at all positions of the driving excentric 105 between zero and 180 degrees, and between 180 and 360 degrees, shows 50 pressure in the clamp as indicated by line 161.

Fig. 7 shows a different arrangement of the balance mechanism, wherein the two arms 237" and 237' of the transforming lever change both their effective lengths g and h in relation to the turn of the driving excentric 205. Working with the same tension of the spring as in sample of Fig. 6, the pressure in the clamp has the amount shown at line 261. At 0 degree the pressure has the amount P' , at 45 degrees the maximum P'' , 55 and will decrease to P''' at 180 degrees. The knife cuts into the material at this maximum pressure, which is very advantageous, and because the expiration of the cut can be done with less pressure, the cut will be finished with decreasing pressure in the clamp, which is obtained by line 261 from P'' to P''' .

The clamp will start to press any pile, no matter how high it may be, between zero and maximum, with the same amount of pressure. But a low pile does not need as much pressure as a high one. In Fig. 8 is shown a new arrangement between the balance mechanism 337, 338, 339, which is alike the one of Fig. 7, and the transmission lever 363. With the down-movement of the 75

press beam, the effective arm length i of the lever 363 decreases to i' , which will produce a decreasing pressure in the clamp as shown by P' and P'' at line 362 Fig. 8a. In direction H is marked the height of the piles from zero to maximum, and line 364 indicates the meeting of clamp and pile for all heights of piles. Above line 364, Fig. 8a line 362 shows the amount of pressure at these meeting positions. Line 262, Fig. 8a, represents the pressure amount at the meeting positions of a clamp formed like Fig. 7.

In Fig. 9 is a two-arm lever arranged between the driving eccentric 405 and the balance mechanism. The spring tension f is here in rest position very low and will increase with the turn of the eccentric, but not reach the amount of the maximum pressure in the clamp. This object, to obtain a maximum pressure as provided in Fig. 6, but with a highest spring tension of only about one half of Fig. 6 is the result of the arrangement of transforming lever 437. Its effective arm lengths g and h , with the above described spring tension, result in the pressure in the clamp as shown by line 461. Up to 45 degrees the pressure is increased from P' to P'' of more than the double amount, which gives a smooth and shakeless working clamp.

A further object of the invention is shown in Figs. 10 and 11. For proper clamping of hard and soft stock the pressure amount must be adjustable. A pressure variation is obtained in Fig. 10 by varying the absolute length of arm 537" from k to k' of the transforming lever. This can be done easily, not under the load of the spring tension, by moving the pin 550 in a slot 548 of the lever 537. The movement can be done by hand and the pin 550 tightened with a screw at the wanted position as described in Fig. 1, or a transportation screw with a hand wheel could be used to change the distance of pin 550 and pin 542. A constant spring tension at rest position of the machine combined with the adjustability of arm 537" allows a pressure variation as shown between lines 561 and 561', respectively between line 561 and zero.

In Fig. 11 the length of the arm 628 of the transmission lever is adjustable from 1 to 1', with about the same result as described at Fig. 9. Pin 636 can be moved in slot 648. Lines 661 and 661' are showing the limits of pressure variation in the clamp by an adjustment of one half of the length of arm 628.

In both cases, as described in Figs. 10 and 11, it is an important feature, that the variation of the absolute arm length of a lever takes place without, or nearly without, a movement of the press beam in rest position of the machine. This is obtained by the arrangement of the slot in about the direction of the circle direction, in which the pin 550 or 636 can be moved, which means: in about right angle α to the spring 541 in Fig. 10 or to the connecting rod 638 in Fig. 11.

I claim as my invention:

1. In a paper cutting machine having a driving mechanism and a paper clamp, a connecting rod and an elastic member each connected to said driving mechanism, a lever to different points of which said rod and said elastic member are operatively connected, and means for reciprocating the clamp actuated by said lever.

2. In a pressure balancing mechanism for a paper cutting machine, having a driving mechanism and a paper clamp, an angular lever, a rigid connecting rod connected to said lever at one point thereof and to the driving mechanism,

an elastic connection between another point of said lever and the driving mechanism and means for transmitting motion from a third point of said lever to said clamp.

3. In a paper cutting machine having a paper clamp and a driving mechanism, a two-arm lever, rigid means connecting said lever to the driving mechanism, a connection of variable length connecting said two-armed lever to said driving mechanism, a compression spring tending to lengthen said variable connection and means for transmitting motion from said two-armed lever to the clamp, the arrangement being such that difference in the tension of the spring is compensated by variations of the effective length of the arms of the lever which is obtained by turning the lever.

4. In a paper cutting machine, a lever pivoted to the frame of said machine, means for oscillating said lever, a cutting blade and a press bar, means for actuating said blade from one arm of said lever, means for actuating said press bar from another arm of said lever, said last named means comprising a second lever pivoted on the frame of the machine, a floating lever slidably pivoted thereto, a rigid connecting rod pivoted to said floating lever and to an arm of said first named lever and a shaft of telescoping sections pivoted to said floating lever and to the arm of said first named lever to which the rigid connecting rod is pivoted, and a coil spring on said shaft tending to extend said shaft to its maximum length.

5. The device as claimed in claim 4, and means on said shaft for regulating the maximum and minimum length of said shaft.

6. The device as claimed in claim 4 wherein there are means for adjusting the point of connection of said shaft to said floating lever.

7. In a paper cutting machine, a cutting blade, a press beam, a two armed lever mounted on the frame of the machine, means operatively connecting said cutting blade to one arm of the lever, and both elastic and rigid means connecting the other arm to a floating lever and operative connections between said floating lever and said press beam.

8. A paper cutting machine comprising a frame, a table mounted in said frame for supporting the paper to be cut, a cutting blade slidably mounted in the frame, a press beam supported above the table, a two-armed lever, means for oscillating said lever, operating connections between one arm of said lever and the cutting blade, operating connections between the other arm of said lever and the press beam, said last named operating connections including a floating lever, a connecting rod of fixed length pivotally connected to one point of said floating lever and to one arm of the two-armed lever, a shaft of two telescoping parts pivotally connected to another point of said floating lever, and to the same point of said two-armed lever as the connecting rod, a compression spring surrounding said shaft and tending to elongate the shaft, a three armed lever pivoted on said frame and having a slot in which a pin on the floating lever is slidable, a link pivotally connected to one arm of said three armed lever and to one end of the press beam, a bell crank lever pivoted to said frame, a second link pivoted to the bell crank lever and to the other end of the press beam, a shaft connecting said bell crank lever to the three armed lever to guide the motion of the links and a spring secured to said frame and to the three armed lever tending to hold said press beam in an elevated position.

9. The device as claimed in claim 1 in which the construction and arrangement of the lever, rod elastic member and the reciprocating means is such that the tension exerted by them on the clamp lessens as the clamp is lowered.
10. In a paper cutting machine, a clamp, means for operating said clamp including a two armed lever and means for oscillating said lever, a second two armed lever, a rod connecting said two-armed levers and a telescopic extensible rod also connecting said two-armed levers, a spring tend-

ing to elongate said telescopic extensible rod, the arrangement and construction being such that in the lowest position the telescopic rod makes an angle of substantially 90° with the arm of the second named lever and the connecting rod makes an angle of less than 45° with its arm of the second named lever and the first said angle decreases while the second said angle increases with the operation of the mechanism from this position.

FRITZ LAESSKER. 10
